(57) **CLAIM**

The ornamental design for a flask, as shown and described.

DESCRIPTION

FIG. 1 is a bottom plan view of a flask showing my new design;

FIG. 2 is a side elevational view thereof, all side elevational views thereof being identical;

FIG. 3 is a top and side perspective view thereof; and,

FIG. 4 is a top plan view thereof.

The broken line showing of the central region of the bottom surface is for environmental purposes only and forms no part of the claimed design.
